(57) **CLAIM**

The ornamental design for an integrated solar energy and bicycle providing means, as shown and described.

DESCRIPTION

FIG. 1 is a front top and right perspective view of an integrated solar energy and bicycle providing means showing my new design invention;

FIG. 2 is a rear, top, left, perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown represent unclaimed subject matter and form no part of the claimed design.
